NOEL PEMBERTON-BILLING, OF LONDON, ENGLAND, ASSIGNOR OF ONE-HALF TO WORLD RECORD LIMITED, OF CROMWELL WORKS, LONDON, ENGLAND, A BRITISH COMPANY.

PICTURE PROJECTING OR EXHIBITING MEANS.

Application filed May 8, 1925. Serial No. 28,841.

This invention consists in improvements in or relating to picture-projecting means and has for its object to provide means whereby pictures may be projected on to a screen or otherwise viewed to illustrate the subject-matter of a gramophone or like record. The projection of the pictures will be synchronous with the passages in the subject-matter of the record which it is desired to illustrate.

According to the present invention, apparatus for the above purpose comprises in combination a "picture-band", a "stylus" operative as a stop, means to impart movement to said "stylus", and shifting means movable transversely to the path of the "stylus" and operatively connecting between the "stylus" and the "picture-band" for shifting the latter when the "stylus" attains a predetermined position in relation to the shifting means. Conveniently either the "stylus" or the shifting means, preferably the latter, moves in a circular path and the other moves in a path transverse thereto, for example a path which is substantially radial to that of the circular movement.

Where the term "picture-band" occurs herein, this term is to be understood as including any arrangement or collection of pictures which are preferably disposed side-by-side either in contiguity with one another or separated from one another by a space.

The term "stylus" is to be understood throughout the specification as including a pin or other member which serves as a stop for the shifting means and where herein-after the term "track-member" is employed it is to be understood as including a gramophone or like record having a spiral, helical or other impression groove thereon or any other member in or on which the required track is provided.

More particularly the present invention comprises in combination a picture-band, a track-member in the form of or bearing on it a spiral track, a stylus to engage said spiral track, means to impart relative rotation between the said track-member and the stylus about the axis of rotation of the track-member, and shifting means operatively connected between said stylus and the picture-band for shifting the latter when the stylus at-

tains a predetermined position or positions along said track. In one form of the invention the spiral track is the spiral record-groove of a gramophone or like record, and the stylus is the sound-box stylus of the gramophone or the like which engages with-in the record-groove.

In order that the invention may be more clearly understood one preferred construction will now be described in detail, by way of example only with the aid of the accompanying drawings, in which—

Figure 1 is a perspective view of the apparatus according to the invention shown as applied to the turntable of a gramophone or like device;

Figure 2 is a central longitudinal section through the apparatus illustrated in Figure 1;

Figure 3 is a view looking from the left of Figure 2 with the front cover of the apparatus removed;

Figure 4 shows in elevation the inner side of the front cover of the apparatus;

Figure 5 illustrates the type of picture-band employed;

Figure 6 illustrates the clip by which the pictures are secured in position;

Figure 7 illustrates the shifting means employed; and

Figures 8, 9 and 10 illustrate successive positions occupied by a clutch-actuating member employed in the apparatus.

Like reference numerals indicate like parts in the several figures of the drawings.

The track-member is rotatable and is conveniently, as shown in Figures 1 and 2, a gramophone disc-record 1 bearing on it a spiral track. For the sake of clearness this spiral track is not indicated in precise detail. As usual the record is borne upon a turntable 2 rotating about a fixed centre.

The shifting means comprise a device which is frictionally engaged with the track member or record and is shown clearly in Figures 1 and 7. It comprises a curved member 3 having a notched arcuate edge 4 to be engaged by a stylus 5 which, in the example shown, is the stylus of a gramophone sound-box shown in chain lines at 6. With the member 3 is associated a segmental member 7, the periphery of which is rough-

ened at 8. In the member 7 there is an ar-
cuate slot 9 for the purpose which will be
more clearly explained hereinafter. The
members 3 and 7 are clipped together at
10 by means of a headed pin on the member
7 which passes into a key hole slot in an in-
turned end of the member 3. At the other
end of the latter another inturned end 11 is
formed with a central aperture 12 which
10 coincides with the similar aperture in the
member 7 so that both apertures pass over
the central spindle of the turntable 2 where-
upon the members 3 and 7 assume the position
shown in Figure 1.

15 It will be understood that as the stylus 5
traverses in a more or less radial direction
towards the centre of the record during the
time that the record is being played the
stylus will pass from engagement with one
20 of the notches in the member 3 of the shifting
means 3, 7, and friction between the
track-member and that means will there-
upon move the latter to bring a face of the
next notch into engagement with the stylus.
25 The latter acts as a stop to hold the shifting
means until it (the stylus) has again
moved sufficiently to free it from that notch
and so on in succession through all the
notches. If required, to reduce friction be-
30 tween the shifting means and the surface
of the record 1 the shifting means may be
carried on feet or pads 12 such that the
friction between them and the record surface
while being sufficient to move the shifting
35 means when the stylus leaves one of the
notches, will not be sufficient to impede un-
duly the operation of the motor which drives
the turntable 2.

40 The picture-projecting means is enclosed
within a casing 13 having at its forward end
a cylindrical container 14 enclosed by a re-
movable front cover 15. Within the casing
13 there is a main spindle 16 carried at one
45 end in a bearing 17 mounted in the back of
the cylindrical container 14 and at the other
end in a journal bearing 18 mounted on a
transverse portion or wall constituting part
of the casing 13.

50 On the spindle 16 is slidably mounted a
sleeve 19 which carries a cam disc 20 bearing
on it a cam 21. The sleeve 19 is slotted
55 at one end so that the slots engage
radial pins 22 extending outwardly from op-
posite sides of the spindle 16. Thus the
pins in engagement within the slots permit
sliding movement of the sleeve in respect of
the spindle but prevent relative rotation of
60 those parts. A light coiled spring 23 held in
compression between the end of the sleeve
19 and a boss 24 fixed on the spindle 16
tends to press the sleeve 19 always towards
the right of Figures 1 and 2.

At the other end of the sleeve 19 there is
65 a second disc 25 bearing on it two teeth 26
which are adapted to be engaged by project-

ing pins 27 which are carried on a rubber-
tyred track-wheel 28.

The wheel 28 is carried on a sleeve 29
70 rotatably mounted on the exterior of the
bearing 18.

Disposed in the path of the cam 21 is a
fixed stop 30 supported from bracket mem-
bers 31 which extend across between oppo-
site side walls of the casing 13. When the
75 high part of the cam 21 is in engagement
with the fixed stop 30, as shown in Figure 2,
the teeth 26 are held clear of the pins 27
so that the track-wheel 28, which engages
through the slot 9 with the surface of the
80 record 1 and is rotated thereby, rotates
freely without turning the spindle 16. When
the high part of the cam 21 passes from en-
gagement with the stop 30 the sleeve 19
moves to the right of Figures 1 and 2 so that
the teeth 26 then lie in the path of the pins
85 27 and are engaged by them.

Extending from the boss 24 on the spindle
16 is a radial arm 32 in the outer end of
which is pivoted a link 33 having a balance
90 weight 34 secured to or formed as part of it.
The outer end of the link 33 is pointed and
engages with the roughened margin 8 of the
member 7.

As will be explained hereinafter, the
spindle 16, by means of the mechanism just
described, is intermittently rotated and dur-
ing each intermittent rotation it effects the
shift of one picture for the next. The means
effecting this shift of position of the pic-
ture-band are as follows:—On the end of the
95 spindle 16 is secured a member 35 having a
pin 36 extending from it in the direction of
the axis of the spindle 16. When the spindle
is rotated the pin 36 engages with a tooth of
a toothed wheel 37, a complete revolution
100 of the spindle 16 advancing the member 37
through an angular distance equivalent to
that of one tooth space. A back stop pawl
member 38 is held by means of a spring 39
so that its end 40 engages the teeth of the
member 37 to prevent retrograde movement
105 of that member while allowing it to be
turned by the pin 36.

The member 37 is carried at one end of
110 a hub 41 which is rotatably mounted on a
spindle 42 secured by means of a bolt 43 to
the back wall of the cylindrical container
14. At the other end of the hub 41 and
115 spaced from the member 37 is a disc 44
shown clearly in Figure 3. In this disc are
formed two slots 45, and two pins 46 project
outwardly from it. The picture-carrying
member (i. e. the picture-band hereinbefore
120 referred to) is in the form of a disc having a
plurality of pictures 470 equidistantly spaced
apart near the margin of the disc. This is
shown clearly in Figure 5. The member
47 has slots 48 adapted to register with the
125 slots 45, and has orifices 49 which are adapt-
ed to pass over the pins 46. It will be

noticed that the pins 46 are unequally spaced from the centre of the disc 44 so as to facilitate correct assembly of the picture member.

After the slots 48 of the picture member

- 5 have been passed over the pins 46 a clip 50, Figure 6, is applied so that slots 51 in it pass over the pins 46 whereafter it is slid so that spring tongues 52 enter the registering slots 48, 45 in the picture member and 10 the disc 44 respectively. Thus the picture member is held firmly between the clip 50 and the disc 44, and is unable to move angularly in relation to the disc 44.

The front cover 15 enclosing the picture member is in the form of a circular plate 15 and is held in position by means of a screw 53 entering a screw-threaded orifice in the spindle 42. On its outer surface the front cover 15 is formed with tubular portions 54 20 in which are received legs 55 held therein by means of a set-screw 56, the latter enabling the height of the legs 55 to be adjustable. It also carries a tubular socket 57 in which is slidably received another tube 58 25 carrying a projector lens 59.

On the inner or back surface of the cover 15 there is a plate 60 having in it an aperture 61 the size of which is substantially the same as that of an individual picture on the 30 member 47. The plate 60 is rotatably mounted centrally in the cover plate and can be moved by means of a handle 62 projecting through a slot in the cover plate to the front thereof.

35 In the casing 13 is a removable top cover 63 in which there is a fitting for the reception of a carrier for a lamp 64, the light from which, aided by a reflector 65, is projected through an aperture 66 in the back 40 wall of the casing 14, thence through the picture strip and through aperture 61 and an aperture in the front cover 15 to the projector-lens 59.

The operation of the apparatus is as follows:—

With the parts in the position illustrated in Figures 1 and 2 the wheel 28 is continuously rotated as the record 1 rotates without, however, turning the spindle 16 as the 50 teeth 26 are disengaged from the pins 27. Figure 8 shows, looking from the right of Figure 2, the position of the arm 32 and link 33.

55 As the stylus 5 travels in the spiral track of the record surface it will be moved radially inwards, and will eventually pass from engagement with the notch on the member 3 by which the latter is, for the time being, held stationary. The shifting device will then be suddenly rotated rapidly to bring the next notch into engagement with the stylus 5 and in so doing the roughened margin 8, upon which the pointed end of the link 33 rests will impart a push to the end 60 of that link and will throw it approximately

into the position shown in Figure 9. This movement frees the high part of the cam 21 from engagement with the stop 30 and allows the tooth 26 to be moved into the path of the pins 27. The latter then carry 70 the teeth with them and rotate the disc 25 and with it the spindle 16 and member 35 so that the pin 36 makes one complete rotation and advances the member 37 through an angular distance equal to one tooth space. 75 This results in a change of the picture projected through the lens 59 as will be readily understood.

Towards the end of a complete rotation of the spindle 16 the arm 32 and link 33 assume the position shown in Figure 10 and during the last stages of the rotation of the spindle the link drops by gravity to the position shown in Figure 8 and the arm 32 is arrested in such a position that the high 85 part of the cam 21 remains in engagement with the stop 30 thereby moving the teeth 26 out of the path of the pins 27. A similar cycle of operations is repeated each time that the stylus 5 passes from one notch to 90 the next in the member 3.

The member 60 serves, by means of the slot 61, to register the projected picture accurately on the screen or the like on which the picture is viewed and focussing of the 95 lens 59 is brought about by sliding the tube 58 within the tube 57.

The notches in the member 3 may be, if desired, so spaced that there is a uniform interval of time between the change of each 100 picture for the next.

In such a case the pictures which serve to illustrate any particular record will be so chosen or designed as to illustrate the subject-matter of the record at the particular 105 instant of change. Alternatively individual portions of the record can be selected beforehand for illustration and the notches formed on the member 3 accordingly so that a picture is brought on to the screen at the moment when it is desired to illustrate the particular feature selected. In the latter case the member 3 would only serve for one particular record whereas in the former case one member 3 will serve for every record. 110

While I have illustrated and described one embodiment of my invention, it will be understood that it is not limited thereto but may be otherwise embodied within the scope 115 of the appended claims.

What I claim as my invention and desire to secure by Letters Patent is:—

1. The combination with a revolving member having a track thereon, of means movably guided by the track, a picture strip at an angle to the revolving member having a series of pictures thereon positive actuating means associated with the revolving member imparting movement to the picture strip, whereby the pictures are successively 120 125 130

displayed, and means for controlling the movement so imparted, said last-mentioned means being associated with the track-guided means and controlled thereby.

- 5 2. The combination with a revolving member having a track thereon, of a stylus movably guided by the track, a picture strip at an angle to the revolving member having a series of pictures thereon, positive actuating means associated with the revolving member imparting movement to the picture strip, whereby the pictures are successively displayed, and means for controlling the movement so imparted, said last-mentioned 10 means being associated with the stylus and controlled thereby.

- 15 3. The combination with a revolving member having a track thereon, of a stylus movably guided by the track, a picture strip having a series of pictures thereon, means associated with the revolving member for imparting movement to the picture strip, whereby the pictures are successively displayed, means controlling the movement so 20 imparted, said last-mentioned means comprising a clutch effective for transmitting motion from the movement-imparting means to the picture strip, and stylus-controlled means for intermittently operating the 25 clutch.

- 30 4. The combination with a revolving member having a track thereon, of a stylus movably guided by the track, a picture display device, a picture strip associated with the picture display device, means associated with the revolving member for imparting movement to the picture strip, whereby the pictures are successively displayed, means controlling the movement so imparted, said 35 last-mentioned means comprising a clutch effective for transmitting motion from the movement-imparting means to the picture strip, and stylus-controlled means for intermittently operating the clutch.

- 40 5. The combination with a revolving member having a track thereon, of a stylus movably guided by the track, a picture display device, a picture strip associated with the picture display device, means associated with the revolving member for imparting movement to the picture strip, said movement-imparting means comprising a friction wheel which engages the revolving member, means controlling the movement imparted by the friction wheel, said last-mentioned means comprising a clutch effective for transmitting motion from the friction wheel to the picture strip, and stylus-controlled means for intermittently operating 45 the clutch.

- 50 6. The combination with a revolving member having a track thereon, of a stylus movably guided by the track, a picture display device, a picture strip having a series 55 of pictures thereon associated with the pic-

ture display device, means associated with the revolving member for imparting movement to the picture strip, whereby the pictures are successively displayed, said movement-imparting means comprising a friction wheel which engages the revolving member, means controlling the movement so imparted, said last-mentioned means comprising a clutch effective for transmitting motion from the friction wheel to the picture strip, and stylus-controlled means for intermittently operating the clutch, said clutch-operating means comprising a plate having a serrated edge which engages the stylus, a toothed surface associated with said plate, a pawl engaging said toothed surface and operatively connected to the clutch, whereby motion of the serrated plate controlled by the stylus, is made effective for operating the clutch.

7. The combination with a revolving member having a track thereon, of a stylus movably guided by the track, a picture display device, a picture strip having a series of pictures thereon associated with the picture display device, means associated with the revolving member for imparting movement to the picture strip, whereby the pictures are successively displayed, said movement-imparting means comprising a friction wheel which engages the revolving member, means controlling the movement so imparted, said last-mentioned means comprising a clutch effective for transmitting motion from the friction wheel to the picture strip, stylus-controlled means for intermittently operating the clutch, said clutch-operating means comprising a plate having a serrated edge which engages the stylus, a toothed surface associated with said plate, a pawl engaging said toothed surface and operatively connected to the clutch, whereby motion of the serrated plate, controlled by the stylus, is made effective for operating the clutch, and means maintaining the picture strip in fixed position during the time of display thereof.

8. The combination with a gramophone having a record support and a record thereon, of a stylus guided across the record, stylus-controlled means for successively displaying pictures, said means including a member having notches therein, said stylus being adapted to engage the notches, a picture strip moving mechanism, and means associated with the picture strip moving mechanism controlled by the movement of said notched member when the stylus is moved out of engagement with one of the notches into engagement with a succeeding notch, to effect the operation thereof.

9. Apparatus of the class described comprising in combination with a picture-band, a stylus, means for imparting a movement to the stylus, shifting means movable trans-

versely to the path of the stylus and controlled by the stylus, picture strip operating mechanism and means operatively engaging the shifting means and controlling the operating mechanism.

10. The combination with a gramophone having a record support and a record thereon, of a tone arm having a stylus for engagement with the record and movable radially across the record, a notched shifting means engaging the stylus, picture projecting mechanism for successively projecting pictures, and means operatively engaging the shifting means and controlling the projecting mechanism.

11. The combination with a gramophone having a record support and a record thereon, of a stylus for engagement with the record and movable transversely with respect thereto, a picture-band, a picture-band moving mechanism frictionally engaging the record, a clutch interposed between said moving mechanism and the picture-band, and stylus controlled means for intermittently operating the clutch to successively advance the picture strip.

12. The combination with a gramophone having a record support and a record thereon, a stylus movable across the record, a curved notched member over the record whose notches are adapted to engage the stylus and to become successively disengaged by the movement of the stylus across the record, said curved member being frictionally engaged with the record whereby it is moved when the stylus moves from engagement with one notch to engagement with another notch, a picture display mechanism for successively projecting pictures, and means operatively engaging the curved member and controlling the picture display mechanism.

13. The combination with a revolving member having a spiral track, of means guided in the track, and a picture strip display mechanism operatively associated with said means, driving mechanism for positively moving the strip, and a control element for the driving mechanism operated by said means.

50 14. The combination with a revolving

member having a track therein, of a movable stylus guided in the track and operated thereby, a revolving picture strip, means for revolving the picture strip, a clutch interposed between the picture strip and the revolving means therefor, and clutch-operating means controlled by said stylus.

15. The combination with a turntable having a central pin, a spirally grooved record on the turntable, a shifting mechanism resting on the record and received on the central pin of the turntable, said shifting mechanism including a curved strip having a plurality of notches in one edge thereof and a plate having a notched segmental surface, and a projector mechanism having a support at the central pin of the turntable and having a fixed support beyond the turntable, a stylus engaging the record and movable with respect to the notched element of said shifting mechanism, a shaft in the projecting mechanism, a wheel on the shaft engaging the record and rotated thereby, a clutch for transmitting motion from the wheel to the shaft, means engaging the toothed segment of said plate member of the shifting means for controlling the operation of the clutch, and a picture-band operated by the rotation of said shaft.

16. A picture projecting attachment for gramophones including a projector having a picture-band advancing mechanism and a shifting mechanism for controlling the operation of the picture-band advancing mechanism, said picture-band operating mechanism including a rotating shaft, means for rotating the shaft, a clutch between the shaft and the rotating means, a pawl on the shaft, said shifting means including an element supported on the turntable of a gramophone and having a stylus engaging segment and a toothed segment for engagement with said pawl, said pawl serving to actuate the clutch when the shifting mechanism is advanced, and a cam for releasing the clutch when the picture-band has advanced a predetermined distance.

In testimony whereof I affix my signature.

NOEL PEMBERTON-BILLING.
